UNITED STATES PATENT OFFICE.

MILTON R. WILSON, OF SAN FRANCISCO, CALIFORNIA.

METHOD AND MEANS OF FORMING BARREL TUMBLERS.

Application filed November 22, 1924. Serial No. 751,495.

My invention has for its object the shaping of a tumbler during the process of its manufacture whereby the upper portions of the conical form are rounded or given a curvature inwards so that the finished tumbler has a barrel shape.

It is well known that this shape has particular advantages in transportation and handling and reduction in liability to breakage.

This turning over of the upper walls of the tumbler into the curved or barrel shape, I accomplish by rotating the tumbler and at the same time pressing against opposite sides of the rotating tumbler a pair of surfaces having in cross section the desired shape of an element of the tumbler walls. These surfaces are advanced with respect to the tumbler axis while the tumbler rotates and during the said advancement they exert an inward pressure against the tumbler wall.

It is to be understood of course that this takes place during the time that the tumbler is at a high temperature and that the glass is therefore sufficiently plastic to take the new form under the pressure of the said forming surfaces.

By referring to the accompanying drawings my invention will be made clear.

In the drawings, Fig. 1 shows a portion of a carriage adapted to support a plurality of tumblers in the intermediate stages of their finishing, with one of the tumblers and its spinning table shown in cross section.

Fig. 2 is a part section and part perspective view of a tumbler after it has been formed into the barrel shape and showing the relative position of the forming surfaces and their operation at the latter portion of the forming step.

Fig. 3 is a plan of Fig. 2.

Fig. 4 is one of the forming surfaces of Fig. 2 in perspective and with a projected front view indicated by the dotted lines and a series of right angled cross sections of the said surface to show the progressive curvature.

Fig. 5 is an alternate adaptation of my invention as applied to a conventional glazing table.

Throughout the figures similar numerals refer to identical parts.

A pair of tumblers which have previously

been molded and thereby partially shaped are indicated by the numerals 1 and 2. The lower part of these molded tumblers have been properly shaped in the mold as shown at 3 and 4 respectively. The tumblers have then been transferred to the cups 5 and 6, which cups are carried upon a spindle 7 in bearings 8, 8, on the table or carrier 9 and are adapted to be rotated about the axis of the spindle 7, by any conventional means as the pulley 10 and traveling band 11, shown somewhat diagrammatically in Fig. 1, but well known.

The tumblers are also preheated to the proper degree so that the glass will flow under the pressure of my forming surfaces. A pair of surfaces having preferably plain or straight portions at 12 and 13 are twisted in their length to have a curvature at their ends 14, 15, respectively, corresponding with the desired curvature of the upper portion of the finished tumbler.

At 16 is shown a tumbler in process of being formed into the barrel shape and at 17 is shown such a tumbler having the finished barrel form. The forming surfaces are carried in any alignment-maintaining-structure as for example the rod 18 carried in the supports 19, 20, and operated in any conventional manner as by the handle 21, whereby the supporting member 18 carrying the planes 12, 14, and 13, 15, may be advanced from the dotted position 22 to the full line position.

During the movement the tumbler is rotating about its axis of symmetry, as indicated by the arrow 23, and the forming surfaces are advanced in the direction and to the degree indicated by the arrow 24.

It will now be seen that, when the tumbler 2 comes into the position 16 and the forming surfaces are advanced as indicated by the arrow 24, while the tumbler is spinning as indicated by the arrow 23, the glass being in a proper plastic condition, the curvature of the forming surfaces between 12 and 14 and between 13 and 15 will press inward the upper portion of the tumbler surface from the contour indicated at 2 until the tumbler has been formed into the barrel shape indicated at 17. The surfaces are then withdrawn in the reverse direction to the arrow 24 and the tumbler is transferred on the carriage 9 clear of the forming surfaces and simultaneously therewith a new

tumbler ready to be formed as indicated by 2, is transferred into the position 16 ready for a repetition of the forming steps.

The twist or the curvature which is introduced into the forming surfaces 12, 14, and 13, 15, is indicated progressively by the cross sections 25, 26, 27, 28 and 29 of Fig. 4. The section at 25 being relatively straight and conforming to the side of the upper portion of tumbler 2. The ultimate curvature as at 29 corresponds with the upper curvature of the finished barrelled tumbler as shown at 17. The intermediate sections 26, 27, 28, indicate the progressive curvature from the section 25 to the section 29 as the forming surface travels over the plastic surface.

Referring particularly to Fig. 5, showing a modification of the adaptation of my invention; a conventional glazing table is shown at 30 on which a plurality of tumblers 31, 32, 33, 34 and 35, which have been or are being glazed, as by flames projected against their upper edges while the tumblers are traveling about the circular path as indicated by the arrow 36 about the center 37 in the conventional way.

At 38 is shown an arm pivotally supported about the center 37. The parallel movable rod 41 is carried in the bearings 39 and 40 and is movable by the lever 42 in the same manner as the structure indicated in Fig. 2, whereby the forming surfaces 43, 44, may be advanced by the movement of the handle member 42 in the radial direction shown by the arrow 45.

The tumbler at 33 is in the process of being barrelled and is being rotated in its supporting cup by any conventional means as indicated in Fig. 1 and during this rotation and while the table is moved, as shown by the arrow 36, the surfaces 43, and 44, are moved radially as shown by the arrow 45 forcing the upper surfaces of the exterior of the tumbler into the turned or barrelled shape. The upper edge being thus reduced in diameter as it proceeds from the position 33 to the position 34 as indicated by the edge 46. The forming surfaces have at such time moved from the full line position to the dotted position.

In order that the arm 38 should move synchronously with the table 30 while this barrelling process is proceeding, I provide the spring latch 50 which successively engages notches corresponding with each tumbler, one of these notches is shown at 51 and frictionally holds the arm 38 to move synchronously with the table while the forming operation is progressing. The latch 50 is held in the notch 51 during the time that the table moves the arm 38 from the full line to the dotted position, at which latter time the operator by pulling the arm in the direction of the arrow 55 shifts the apparatus

from the dotted position back to the full line position. Notch 52 which has now arrived in the position of 51 will now be engaged by the said latch and the forming operation will then be repeated on tumbler 32.

Tumbler 34 which formerly occupied the position 33 will now be transferred to the position 35 as a finished tumbler.

A conventional stop is indicated at 56 by which the movement of the forming surfaces is arrested at the same point, thus assuring a standardization of the tumbler shapes.

In lieu of the movement of the forming surfaces by the lever and connections 42, their movement may be produced automatically as by the roller 61 rolling upon the cam position surface 60. During its travel from the full line to the dotted position, the surfaces will be forced in the direction of the center 37, thus automatically barreling the tumbler as the table 30 rotates in the direction 36. When the roller arrives at its dotted position it rides free of the cam surface and may then be displaced therefrom and returned to the full line position for a second operation. The spring 62 being under compression during the roller travel on the cam restores the surfaces to the full line position.

It is understood that the various steps in forming and finishing a tumbler, both before and after the barrelling, may be carried out in any conventional manner and form no part of my invention, and it will also be understood that while I have shown a pair of twisted surfaces having a straight line motion, other shapes of forming surfaces and other motions corresponding with such shapes may be given whereby the exterior surface of the conical tumbler may be compressed while it is rotating into a barrelled form without departing from the spirit of my invention and I desire to be understood as claiming all such variations.

I have found that where the tumblers are formed at a rapid rate as from three to ten a minute the forming surfaces become quite hot and the surfaces may be advantageously cooled by a water cooling jacket against their outside surfaces. Also the said surfaces may be caused to move by a foot pedal or by connection with any automatic or power means. All such variations although not specifically shown and described, are within my inventive concept.

I claim:

1. The process of shaping a glass tumbler which consists in rotating the heated tumbler about its axis of symmetry while moving the tumbler bodily in a given direction and presenting against the sides of the tumbler a plurality of forming surfaces while also moving said surfaces bodily with the tumbler in said given direction.

2. In an apparatus for forming barrel shaped tumblers, means for rotating the tumblers about their axes of symmetry, a plurality of side forming surfaces, means constructed and adapted to move said surfaces in a direction transversely past the axis of rotation substantially tangent to and also against the tumbler outer walls whereby the said walls are compressed into barrel shape.

3. In an apparatus for forming barrel shaped tumblers, means for rotating the tumblers about their axes of symmetry, a plurality of side forming surfaces, means constructed and adapted to move said surfaces substantially tangent to and also against the tumbler outer walls whereby the said walls are compressed into a barrel shape, said surfaces having a flat shape where they first contact with the tumbler walls and a barrel shaped cross section where they finish their contact with the said walls.

4. In an apparatus for forming barrel shaped tumblers, means for rotating the tumblers about their axes of symmetry, a plurality of side forming surfaces, means constructed and adapted to move said surfaces substantially tangent to and also

against the tumbler outer walls whereby the said walls are compressed into a barrel shape, a transfer carriage for a plurality of said tumblers and engaging means adapted to engage the said surfaces to travel parallel with the transfer movement of the tumblers during the forming of the tumbler into barrelled shape.

5. In an apparatus for forming barrel shaped tumblers, means for rotating the tumblers about their axes of symmetry, a plurality of side forming surfaces, means constructed and adapted to move said surfaces substantially tangent to and also against the tumbler outer walls whereby the said walls are compressed into a barrel shape, said surfaces having a flat shape where they first contact with the tumbler walls and a barrel shaped cross section where they finish their contact with the said walls, a transfer carriage for a plurality of said tumblers and engaging means adapted to engage the said surfaces to travel parallel with the transfer movement of the tumblers during the forming of the tumbler into the barrelled shape.

MILTON R. WILSON.
